UNITED STATES PATENT OFFICE

2,522,483

PLURAL SOAP-CAKE HOLDER

Ferdinand T. Plack, Harrisburg, Pa.; Harry G. Plack, executor of said Ferdinand T. Plack, deceased

Application May 10, 1946, Serial No. 668,879

1 Claim. (Cl. 45—28)

1

This invention relates to soap holders, and especially to a divisible combination of inner and outer receptacles that form a plural soap-cake holder and is a simplification and improvement of my soap holder shown and described in my Patent No. 2,184,085.

One object of this invention is to minimize the number of primarily separate parts, all formed of sheet-metal blanks and united without the need of any extrinsic mechanical means, thereby to minimize the manufacturing cost.

Another object is to provide the outer receptacle and inner receptacle with inter-latching elements that combine to secure the inner receptacle against accidental displacement from the outer receptacle, while permitting the inner receptacle to be removed easily and quickly by simple manipulation, and as quickly and easily replaced in the outer receptacle after both these receptacles having been cleansed internally.

Another object is to form these receptacles with a lower floor and an upper floor, respectively, normally spaced from one another so as to provide a drain-receiving chamber into which the upper floor sheds water from the soap-cakes into the said chamber; the upper floor being removable from the outer receptacle, so the drain-receiving chamber can be thoroughly cleansed; the inner receptacle having no rear wall or side-walls; so easy access to all its parts, by a brush or rag, can be had for thoroughly cleaning all its parts.

Other objects and important features are pointed out or implied in the following details of description, in connection with the accompanying drawings in which:

Fig. 1 is a front elevation of the two receptacles combined in the normal relation, as if seated on a shelf or other level surface.

Fig. 2 is a vertical sectional view, the section being along the line 2—2 of Fig. 1.

Fig. 3 is a top plan view of the outer receptacle alone.

Fig. 4 is a front view of the inner receptacle alone, its front side having a portion broken out and in section.

Fig. 5 is a fragmental detail of a modified form of inter-latching elements at upper-rear.

Referring to these drawings in detail, in which, similar reference-numerals refer to similar parts in the several views, the invention is described in detail as follows:

The outer receptacle 7 is preferably formed of a single sheet of metal bent so as to form a lower floor 8, a rear wall 9, right and left walls 10, a

2

substantially horizontal upper-rear cover-element 11 that includes a keeper or latch-engaging means 11a, and a very low front wall 12 that is only slightly higher, substantially $\frac{1}{16}$ inch higher, than the space between the lower floor 8 and the upper floor 13 which latter is the base-element of the inner receptacle and which is preferably formed with four slots at 13a. In Fig. 2, only one inner wall or partition 14 is shown with tongues 14a extending thru the respective slots of one pair and therein secured by any appropriate means, for instance, by twisting their lower ends and by soldering or welding as indicated at 15 in Fig. 4. The front edge of the floor or base-plate 13 is united with a low wall 13b that preferably extends forward and downward, as more clearly shown in Figs. 2 and 4, forming an arch over the low wall 12, and the latter has its upper-inner edge normally substantially against the wall 13b or the juncture thereof with the floor 13, so the latter cannot be initially moved forward, but may be first raised and then passed forward over the front wall 12.

The wall or partition 14 or 14M has its upper-rear part formed with a detent or latching element 14c or 14d. In Fig. 2, the detent 14c is in interlatching engagement with the keeper or latch-engaging means 11a in a proper relation to be moved upward, but restrained from being moved forwardly initially; and the same operation and effect are accomplished by a similar inter-latching of the elements 14d and keeper 11b of Fig. 5. The element 14c is normally in a slot in rear of the keeper 11a, thereby restrained against lateral movement; and the element 14d is restrained against lateral movement by its engagement with two bosses on its opposite sides, one of which is seen at 9b in Fig. 5. Bosses 12a (Figs. 2 and 3) are normally substantially against the front edge of the upper floor, at the junction of the latter with the wall 13b, so as to restrain the upper floor against forward movement while in its lower position in which the lower floor supports it thru the medium of side-flanges 13c and/or the ears 14a. When it is desired to remove the inner receptacle from the outer receptacle, it is necessary only to grasp the partition and lift it while tilting it rearward, thereby raising the front edge of the floor 13 above the wall 12 and immediately swinging the inner receptacle to the broken-line position of Fig. 2, and then lowering it until its element 14c or 14d is disengaged from the keeper 11a or 11b, whereupon, the inner receptacle is free to be moved away from the outer receptacle 7.

Though only one partition has been described in the foregoing, and though the invention would be complete for a two-compartment soap-holder of this kind, I have shown two counterpart partitions 14, and there is no limit stated or implied as to a single or any number of such partitions.

Each side of each partition is provided with upright bosses or ridges 14e to contact the broad sides of the respective soap-cakes that are to be disposed vertically in the respective compartments between the partitions 14 and the side-walls 16 which latter have ridges 16e for same purpose and to facilitate the draining of water from said broad sides, also to minimize adhesion between the soap-cakes and the compartment-walls; and for similar purposes, ridges 9e are formed on the rear wall 9, and ridges 13e are formed on the upper floor 13. These ridges also serve to rigidify the respective floor, walls and partitions, so as to preclude the necessity of using thick sheet-metal in their construction. Therefore, it is now explained that the contemplated metal's thickness is greatly exaggerated in the accompanying drawings, to avoid confusion of adjacent lines.

This invention is not confined to the precise details of construction herewith shown and herein specifically described, for the invention is susceptible of numerous changes within the scope of the inventive ideas as implied and claimed.

My invention is claimed as follows:

In a plural-compartment soap-cake holder, a divisible combination of an outer receptacle having a lower floor, and an inner receptacle normally and removably seated in said outer receptacle and having an upper floor normally spaced

above said lower floor in a proper relation to shed water from a soap-cake when on the upper floor onto the lower floor, said outer receptacle having a rear wall and a substantially horizontal, upper-rear cover-element that are integrally united with one another, said outer receptacle having right and left walls and a front wall, said front wall being only slightly higher than the space between said lower floor and upper floor and having its upper-inner edge normally seated substantially against said upper floor so as to prevent initial forward movement of said upper floor, said inner receptacle being provided with at least one partition united with said upper floor and having its upper edge normally inter-latched with said upper-rear cover-element in a proper relation to prevent initial forward movement of said upper edge, said inner receptacle being free to be initially moved bodily from its normally seated position to a higher position from which its lower part is free to be moved forward over said front wall to a position from which it can be lowered sufficiently to effect disengagement of its upper edge from said upper-rear cover-element.

FERDINAND T. PLACK.
